UNITED STATES PATENT OFFICE.

HERBERT H. HUTCHINGS, OF ARLINGTON, NEW JERSEY.

FLASH-LIGHT.

1,321,639.

Specification of Letters Patent.

Patented Nov. 11, 1919.

Application filed March 14, 1918. Serial No. 222,421.

To all whom it may concern:

Be it known that I, HERBERT H. HUTCHINGS, a citizen of the United States, and a resident of Arlington, in the county of Hudson and State of New Jersey, have invented a new and Improved Flash-Light, of which the following is a full, clear, and exact description.

This invention relates to flashlights, and has for its general objects to provide means for preventing the weight of the battery from acting on the central contact of the lamp bulb and breaking the bulb loose from the screw base of the lamp, damaging the filament or breaking the cement of the central contact.

A more specific object of the invention is the provision of a novel means within the case of the flashlight for the battery to bear against the same, whereby the said means supports the weight of the battery when the flashlight is inverted.

With such objects in view, and others which will appear as the description proceeds, the invention comprises various novel features of construction and arrangement of parts which will be set forth with particularity in the following description and claim appended hereto.

In the accompanying drawing the figure is a sectional view of a flashlight showing an embodiment of the invention.

Referring to the drawing, 1 designates the shell or casing of the flashlight, 2 a battery therein, 4 the incandescent lamp, 5 the

reflector, 6 the lens. These parts are of usual construction, so that a detailed description thereof is unnecessary.

In the casing 1 is a sleeve 7^b of insulation which is of such length as to extend from the battery to the shoulder 18 of the reflector so that the said sleeve will form an annular shoulder against which the battery bears. On the sleeve is a contact composed of spring members 13 and 14 which are interposed between the central terminal 15 of the battery and the central terminal 16 of the lamp. The sleeve or outer terminal 11 of the lamp is grounded on the metallic disk 10 against which bears a metallic strip or contact 9 leading to the push button or switch of the flashlight.

Having thus described my invention, I claim as new and desire to secure by Letters Patent:

A flashlight comprising a casing, a battery therein, a reflector in the casing, a lamp carried by the reflector, a sleeve of insulation having a uniform internal diameter larger than the reflector, whereby the sleeve surrounds the reflector and extends to the battery to form an internal shoulder against which the battery bears, means for connecting one terminal of the lamp with one terminal of the battery, and means carried by the said sleeve for connecting the other terminal of the lamp with the remaining terminal of the battery.

HERBERT H. HUTCHINGS.
